UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

HEADING-MACHINE.

1,297,429.

Specification of Letters Patent. Patented Mar. 18, 1919.

Application filed May 28, 1918. Serial No. 237,121.

To all whom it may concern:

Be it known that I, RICHARD LESTER WILCOX, a citizen of the United States, and a resident of Waterbury, county of New Haven, and State of Connecticut, have invented 5 certain new and useful Improvements in Heading-Machines, of which the following is a specification.

My invention relates to arrangements by 10 which a series of successively operative tools, such as punches, dies, or the like, may be brought successively into operative position and locked in each of such successive positions adjustably.

15 One of the objects of my invention is to provide a simple and yet efficient locking means by which three of such tools may be locked in operative positions, which positions are themselves adjustable in order that 20 each tool may be moved into exactly the correct position, without affecting the correct position of the other tools.

With these and other objects in view, my 25 invention consists of certain novel features of construction, combination and arrangements of parts as will be more fully described and pointed out in the appended claims.

As an illustration of my invention showing only one of its specific applications, I have shown in the accompanying drawings certain parts of a well-known form of metal heading machine, such as is illustrated in my prior Patent No. 1,036,047 dated August 35 20, 1912. In such machines dies are provided in which is held the wire to be headed. Moving back and forth toward these dies is a gate on which are mounted the punches which operate successively on the wire held 40 in the dies at each reciprocation of the gate toward the dies.

This successive operation is obtained by 45 mounting the punches in a slide which is usually transversely movable on the front of the gate. Mechanism is provided by which at each stroke of the gate the slide is moved transversely to a new position to bring a punch into operative position.

Since all of the parts thus described generally are old in the art, further description of them is unnecessary.

In the accompanying drawings, Figure 1 shows a longitudinal section of one portion of such a metal heading machine with three

55 punches, some of the parts being in machine cross-section and with the top punch in operative position.

Fig. 2 corresponds to Fig. 1 except that the middle punch is in operative position.

Fig. 3 corresponds to the preceding figures, 60 except that the lowermost punch is in operative position, and

Fig. 4 is a front elevation of the slide looking in the direction of the arrow 4 of Fig. 3.

65 In the drawings, 10 is a fixed part of the heading machine used for the purpose of illustration and 11 of the dies held therein. 12 is the reciprocating gate, which is shown in each of Figs. 1, 2 and 3 as in its forward 70 position or at the end of its operative stroke. Mounted on the front of the gate 12 is a slide 13, which by any suitable mechanism, such as shown in my said Patent No. 1,036,047 can be moved transversely as the gate 12 75 reciprocates so as to bring one of the punches 14, 15 or 16 into operative position in alinement with the dies 11. In the machine which I have illustrated three of such punches are to be used, and the machine is 80 what is known as a "three-blow" machine. That is to say, the first operation consists of a blow from the punch 16 (Fig. 1), the second a blow from the punch 15 (Fig. 2), and third a blow from the punch 14 (Fig. 3). 85

90 In work of this nature it is highly essential that the punches be adjusted and held in exact position at each blow of the machine, and because of slight variations in the manufacture of the punches themselves, it is 90 essential that adjustments be provided in which the operative position of any one punch may be adjusted without affecting the operative position of the other punches.

95 In order to accomplish this last named purpose I have illustrated a means comprising a locking member 17, on the slide 13 and having a central notch 18 with beveled faces on either side and also beveled faces 19 and 20 at either end thereof, and a longitudinally movable bolt 21 mounted on the gate 12 and having beveled faces adapted to engage the beveled faces of the notch 18 or the beveled faces 19 and 20 of the locking member 17.

100 105 It will be understood that the bolt 21 is withdrawn during each reciprocation of the gate 12 to permit the slide 13 to be moved

into its next position. Such mechanism may be of any suitable kind such, for instance, as is illustrated in my aforesaid Patent No. 1,036,047. In order to limit the 5 transverse motion of the slide 13, I provide a stop screw 22 adapted to contact with the top of the gate 12 and thereby limit the downward position of the slide 13, and also the stop rod 23 provided with stop nut 24 10 to limit the upward vertical position of the slide 13. The projection 25 of the slide 13 engages with the stop nut 24 as shown in Fig. 3.

The locking member 17 is adjustable in 15 the slide 13 so that its notches and bevel faces may be moved longitudinally of the slide 13 and then locked in place. To this end I have provided the means illustrated best in Fig. 4. The top and bottom of the 20 body portion of the locking member 17 is beveled slightly to engage with corresponding bevels formed at the bottom on the slide 13, and at the top in a clamping member 26. In addition, the clamping face of the clamping member 26 and the supporting face for 25 the locking member 17, in the slide 13 are angularly arranged crosswise of the slide as shown best in Fig. 4. By means of adjusting screws 27—27, the locking member 17 30 may be moved sidewise and because of the said angularly arranged supporting faces, such sidewise motion will cause a corresponding vertical motion to be given to the locking member 17 whereby its locking faces 35 will be adjusted vertically. By tightening the nut 28 on the stem 29 of the clamping member 26, the locking member 17 is then held firmly in adjusted position.

An inspection of Fig. 2 will show that if 40 it is desired to shift the position of punch 15 slightly either up or down, this may be accomplished by loosening the clamping member 26, and by means of the screws 27—27 the locking member 17 may be shifted laterally until, with the bolt 21 in place, the 45 slide 13 is held in such vertical position that the punch 15 is in correct operative position. Such a shifting will not, however, affect the operative positions of the punches 14 and 50 16, because, for instance, when the slide drops to the position shown in Fig. 1 to a point determined by the stop screw 22, the locking bolt 21 will still engage with the bevel face 20 of the locking member 17, 55 though if the latter has been shifted upward in the adjustment just described, it will be obvious that the bolt will not move so far to the right of Fig. 1 as it would before such adjustment. The slide 13 will be locked 60 against any vertical movement, however, if the two beveled faces are in contact. The same explanation applies to the upward position of the slide 13 shown in Fig. 3. On the other hand, by adjusting the stop screw 65 22 or the stop nut 24, as the case may be,

either of the extreme positions of the slide 13 and the corresponding operative positions of the punches 14 and 16 may be adjusted without affecting the operative position of the punch 15 as determined by the notch 18 70 on the locking member 17.

To illustrate the method of adjustment with my novel mechanism, let it be assumed that, while punches 14 and 16 are found to be adjusted so as to be in exact operative position, it is found that punch 15 is too high when in the position of Fig. 2, and must be lowered slightly. This will be accomplished by adjusting screws 27 to move locking member 17 downward and with it notch 18 until, 75 with bolt 21 when in notch 18, punch 15 is located in correct position. But this movement of locking member 17 has lowered punches 14 and 16 below their correct positions, since it was assumed that they would 80 be located correctly before locking member 17 was lowered to adjust the position of punch 15. These two punches must now be properly located without disturbing the position of locking member 17, for that would 85 disturb the positioning of punch 15. Slide 13 is now lowered into the position of Fig. 1 and since punch 16 is too low, it will be brought to correct position by screwing down screw 22, to raise slide 13 and all the 90 punches until punch 16 is in correct position. Similarly, if it had been too high, screw 22 would have been unscrewed. But the adjustment of screw 22 obviously in no way affects the relation between notch 18 and center 95 punch 15 whose location it determines. Again, in order to adjust punch 14, slide 13 is raised to the position of Fig. 3 until projection 25 abuts against nut 24, which is still 100 in its original position to correctly locate punch 14 before locking member 17 was adjusted to position punch 15. But the lowering of member 17 has left punch 14 too low and it is now raised by raising nut 24 to permit slide 13 to go higher. 110

Slide 13 is held up against nut 24 and down against screw 25 by the bevel faces of bolt 21 contacting with the bevel faces 19 and 20 of member 17, the shifting of member 17 simply altering the distance bolt 21 will 115 move to the right in the drawings. It will be understood that the operating mechanism for bolt 21 is supplied with a spring relief member, such as spring 73 of my said prior Patent No. 1,036,047, so that bolt 21 will be 120 moved into locking position only so far as the bevel faces will permit.

From the foregoing, it will be seen that punch 15 is located operatively by shifting the position of member 17 and with it notch 125 18, that punch 14 is located by nut 24 and that punch 16 is located by screw 22. These locating devices being independent of each other, it will be obvious that the adjustment of any one to shift the operative position of 130

the corresponding punch, will not affect the operation of either of the others to locate their corresponding punches.

While I have illustrated my novel adjustment in connection with a heading machine, it will be obvious that it may be used in any device in which it is desirable to locate three tools successively in adjusted operative positions.

10 I claim:

1. In a machine of the class described, a pair of relatively movable members comprising a support and a slide mounted thereon and adapted to be moved longitudinally into any one of three positions, a longitudinally movable bolt having beveled faces and mounted on one of the members, a locking member attached to the other of the members and having a recess adapted 20 to be engaged by the bolt when the slide is in its middle position, the locking member also having beveled faces at either end adapted to be engaged by the beveled faces of the bolt when the slide is in either of its 25 extreme positions, adjustable means to limit the longitudinal motion of the slide in either direction and adjusting means for the locking member whereby the position of the recess may be altered in the direction of motion of the slide.

2. In a machine of the class described, a pair of relatively movable members comprising a support and a slide mounted thereon and adapted to be moved longitudinally into any one of three positions, a longitudinally movable bolt mounted on one of the members, a locking member adjustably connected to the other of the members and having a recess adapted to be engaged by the bolt 35 when the slide is in its middle position, adjustable means to limit the longitudinal motion of the slide in either direction, the bolt and the locking member being adapted to coöperate to hold the slide in the same ex-

treme positions when the locking member is 45 adjusted to alter the middle position of the slide.

3. In a machine of the class described, a pair of relatively movable members comprising a support and a slide mounted thereon 50 and adapted to be moved longitudinally into any one of three positions, a longitudinally movable bolt mounted on one of the members, a locking member attached to the other of the members and having locking faces 55 thereon and adapted to be engaged by the bolt, the locking faces being positioned on the locking member so that as the bolt engages with each of them in succession, the slide is located successively in one of its 60 three positions, adjustable means to limit the longitudinal motion of the slide in either direction, means whereby the locking member may be adjusted longitudinally on the slide to shift the middle position of the slide 65 when locked by the bolt, the locking faces on the locking member being adapted to permit the middle locked position of the slide to be adjusted while leaving the end locked positions of the slide unchanged. 70

4. In a machine of the class described, a pair of relatively movable members, comprising a support, and a slide mounted thereon and adapted to be moved into a plurality of positions, a bolt mounted on one 75 of the members, a locking member connected with the other member, and having means therein to receive the bolt when the slide is in one of its positions, and contact therewith when in both of the extreme positions, adjustable means to limit the motion of the slide in either direction and adjusting means for the locking member whereby its relative position within the slide may be varied, without affecting the engagement of 80 the locking member therewith. 85

RICHARD LESTER WILCOX.
